UNITED STATES PATENT OFFICE.

HARRY ROSS TURNER, OF PHILADELPHIA, PENNSYLVANIA.

COOLING APPARATUS.

1,192,245.

Specification of Letters Patent. Patented July 25, 1916.

Application filed May 15, 1914. Serial No. 838,630.

To all whom it may concern:

Be it known that I, HARRY ROSS TURNER, a citizen of the United States, residing at Philadelphia, in the county of Philadelphia and State of Pennsylvania, have invented 5 certain new and useful Improvements in Cooling Apparatus, of which the following is a specification.

My invention relates to improvements in 10 cooling apparatus, and refers particularly to an apparatus for cooling beer or other beverages, and an object of the invention is the provision of an apparatus which will be absolutely clean, healthy and sanitary under 15 all conditions.

Another object of my invention is the provision of an apparatus of the character and for the purpose stated, which will be small and compact in size, but which will have a 20 very large cooling area or surface, which can be readily taken apart for purpose of cleaning or repair, and which can be quickly assembled or put together.

Another object of my invention is the provision of a cooling apparatus of the character set forth, which in addition to possessing the features named, will comprise very few parts, thus insuring an apparatus of simple and inexpensive construction, which 30 will be practical and efficient in every particular.

With these objects in view the invention broadly stated consists in an apparatus composed entirely of glazed porcelain or 35 other suitable material, comprising a main section or body having cooling passages, caps clamped upon said body and forming a continuation of said passages and means for connecting the caps to supply or 40 discharge the liquid.

The invention further consists of a cooling apparatus embodying novel features of construction, combination and arrangement of parts for service substantially as shown, described and particularly defined by the 45 claims.

In order that the construction in detail and the operation of my apparatus may be clearly understood, and its many advantages 50 fully appreciated, I invite attention to the accompanying drawings.

Figure 1, represents a side elevation of a cooling apparatus constructed in accordance with and embodying my invention. 55 Fig. 2, represents a vertical central longitudinal sectional view of the complete ap-

paratus. Fig. 3, represents an end view of one of the cap members or heads of my apparatus. Fig. 4, represents an end view of the circulating ring or main portion of the 60 apparatus.

Referring by numeral to the drawings in which similar characters of reference denote corresponding parts in all of the views of the drawings:—The numeral 1 designates 65 the main portion of my apparatus, which is made of glazed porcelain or other suitable material, being provided with a series of longitudinal channels or tubes 2, which form circulating passages, the structure providing 70 a cylinder in the form of a ring with the series of circulating passages. These circulating passages are arranged around the ring in pairs, and at their ends communicate with the sockets or seats 3 in the caps or 75 heads 4, such sockets or seats forming the communication for the series of passages of the ring. The caps are also made of glazed porcelain or like material, and are formed with the inner annular flanges 5, which fit 80 snugly around the ring and between the meeting portions of the caps and walls of the passages in the ring are placed packings or gaskets 6, making a water tight connection between the ring and caps. The ring 85 is further provided with an entrance or inlet opening 7, communicating with a similar opening 7, of one cap and with an outlet opening 8 communicating with a similar outlet opening 8' of the other cap. 90

From this construction it will be observed that the liquid enters the inlet pipe 9, passing through the series of passages provided in the caps and rings and passes through the entire series of passages and is discharged 95 through the outlet pipe 10, the inlet pipe when used for beer being connected with the keg and the outlet pipe being connected with suitable connections, each tube for the purpose of making a water tight coupling being 100 provided with screw threads 11. For the purpose of connecting the caps and rings and retaining them in water tight connection I employ a pair of yoke-shaped members 12, each of which is provided with lugs 105 13, which fit in seats 14, in the caps and are thus retained from lateral movement in said caps, and to secure said members I provide the rod 15 which has at one end the head 16, said rod passing through the members 110 17, and at its other end being threaded at 18, to receive the clamping winged nut 18, the

whole structure forming a means for quickly clamping the caps to the ring and securing the members in water tight connection, but easily allowing the parts to be taken apart, 5 as the removal of the winged nut will permit the withdrawal of the rod, the removal of the clamping members and the disconnection of the caps with the ring. The yoke-shaped members are further provided with shoulders 19, which when in position bear upon the flange 20 of the inlet and outlet connection, and serve to retain said connections in proper relation and position in the caps and with reference to the ring.

15 In use it will be understood that the entire apparatus is covered with ice and is connected with the supply receptacle and with the service pipe, and it is evident that the liquid passes from the supply receptacle throughout the entire circulating surface of the apparatus and is brought back and discharged through the outlet, being subjected to the entire circulating surface of the ring and caps and thus being supplied in cold or 25 refrigerated condition.

It will be apparent that the main portion of the apparatus is constructed of glazed porcelain or suitable material and thus no metal surfaces are brought into contact with 30 the liquid which insures a clean, healthy and sanitary condition of the apparatus, and the supply of the liquid in a clean and sanitary condition. Also, the construction of the apparatus of material such as described permits the easy cleaning of the apparatus, and insures its being free from contaminating 35 the liquid which passes through it.

It is evident that the apparatus is simple, inexpensive, and durable in construction, is 40 clean and sanitary and from every point of view will prove entirely practical and efficient.

It will be understood that my apparatus

is capable of use in cooling beer, soda water, 45 or other liquids, and can be used to advantage in railroad stations, department stores, factories and restaurants for cooling drinking water, the apparatus being capable of saving a greater amount of ice when used 50 in this manner.

I claim:—

1. A cooling apparatus of the character described, made of glazed porcelain, consisting of a ring provided with circulating passages, caps connected to said ring and having sockets forming a continuation of said circulating coils, and means for securing said caps in position upon said ring, said means consisting of a pair of clamps engaging said caps and a rod passing through the 60 clamps and having an adjusting nut for binding the clamps upon the caps, said clamps being of yoke shape and having at their ends, a flat portion to rest against the caps and a contiguous lug to engage openings in said caps.

2. A cooling apparatus consisting of a ring provided with a series of longitudinal circulating passages, caps fitting upon the 70 ends of said ring and having sockets forming a continuation of said passages, an inlet pipe mounted in one of the caps and an outlet pipe mounted in the other cap and communicating with the said circulating passages, a pair of yoke-shaped clamping members having lugs engaging said caps to retain said clamping members, and a rod passing through said members and having means for clamping said members in position upon 75 said caps.

In testimony whereof I affix my signature in presence of two witnesses.

HARRY ROSS TURNER.
